Attorney

UNITED STATES PATENT OFFICE.

GEORGE A. RISK, OF BROOKLYN, NEW YORK.

PENCIL AND CASE.

1,337,412.

Specification of Letters Patent. Patented Apr. 20, 1920.

Application filed May 29, 1919. Serial No. 300,628.

To all whom it may concern:

Be it known that I, GEORGE A. RISK, a citizen of the United States, residing at Brooklyn, in the county of Kings and State 5 of New York, have invented certain new and useful Improvements in Pencils and Cases, of which the following is a specification.

This invention relates to pencils and more 10 particularly to a pencil and case of the magazine type in which a quantity of the leads may be stored when not in use and which may be mounted in position on the point of the pencil as the point becomes worn.

One of the objects of the invention is to 15 simplify the structure so that the pencil may be constructed easily and cheaply at a minimum cost and which will be so arranged as to effectively hold the lead in 20 firm position on the point of the pencil so that it will have all of the rigidity of the ordinary wood pencil but may be readily replenished when desired.

A further object of the invention is to 25 provide a device of this character which consists of comparatively few parts and is simple in construction, but durable and well adapted to withstand the rough usage to which devices of this character are ordinarily subjected.

For a full description of the invention and the advantages and merits thereof, reference is to be had to the following description and accompanying drawings, in 35 which:—

Figure 1 is a side elevation of the pencil constructed in accordance with my invention,

Fig. 2 is an enlarged section through the 40 point of the pencil,

Fig. 3 is a perspective view of the clutch element for the lead point,

Fig. 4 is an enlarged transverse section taken on the line 4—4 of Fig. 2.

Referring to the drawings wherein is 45 illustrated the preferred form of my invention, in which like characters of reference indicate like or corresponding parts throughout the several views, the cylindrical pencil case 1 is of any desired length and has the rubber eraser 2 at one end. The opposite end is tapered as indicated at 3 and terminates in a relatively small cylindrical sleeve 4. At the end of the tapered portion, where the latter joins the sleeve 4, the material is pressed inwardly to form an in-

wardly projecting annular ridge 5. The sleeve 4 is slotted at diametrically opposite points as indicated at 6 but the material thus displaced is laterally bent inwardly 60 forming the lateral flanges 7 shown to advantage in Fig. 4.

A clutch element is employed in this end of the pencil and comprises the parallel arms 8 integrally connected together as indicated at 9 and having their opposite ends provided with gripping members 10 projecting toward each other and adapted to co-act to obtain a firm grip on the lead, one of which is indicated at 11. Parallel arms 70 8 are provided with outwardly bent portions 12 forming abutment members which are adapted to engage the annular ridge 5 to limit the inward movement of the clutch element in the point of the pencil. This 75 clutch element is also engaged by the inwardly projecting flanges 7 so that rotary movement of the clutch element in the point of the pencil is prevented. Obviously by virtue of the construction of the parallel 80 arms 8 the same will possess a certain amount of resiliency so that the tendency of the clutch element is to spring to open position. When the clutch element is thrust into the point of the pencil, the spring arms 85 are forced toward each other so that the clutch members 10 will firmly grip the pencil point 11 which is constructed of a soft piece of lead as is well known in the art.

With this arrangement it is possible to 90 use relatively short lengths of lead which may be replenished when they become worn. The interior may contain a quantity of these leads to be removed by removing the rubber eraser 2 from one end of the case. 9 The lateral flanges 7 prevent rotation of the clutch element in the pencil point, the annular ridge 5 is in engagement with the abutment member 12 to limit the inward sliding movement of the clutch element and the restricted length of the arms 8 connected as at 9 form a stop 14 for the end of the lead as shown in Fig. 2 so that a firm pressure may be exerted on the point of the lead when the pencil is in use.

The foregoing description and accompanying drawings have reference to what might be considered to be the approved or preferred form of my invention. I desire it to be understood that I may make such 110 changes in the construction, combination and arrangement of parts, materials, di-

mensions, et cetera, as may prove expedient and fall within the scope of the appended claims.

Having thus fully described my invention what I claim as new and desire to secure by Letters Patent, is:—

1. A casing having a tapered point and terminating in a relatively small sleeve having diametrically opposite slots, the materials displaced by the slots being laterally bent inwardly, a clutch element comprising parallel spring arms having clutch elements projecting toward each other at their ends, and adapted to close when the parallel spring arms are thrust into the said sleeve, the said flanges being engageable with the clutch element to prevent turning of the clutch element in the end of the casing.
2. A casing having a tapered end terminating in a relatively small sleeve, the juncture of the said sleeve and tapered portion being thrust inwardly to form an inte-

rior annular ridge, the said sleeve being equipped with inwardly projecting flanges, a clutch element comprising parallel arms connected together to form an abutment at their inner ends and having their opposite ends equipped with gripping members projecting forwardly of each other and engageable with each other when the said clutch element is thrust into the open end of said sleeve, the said arm being provided with abutment members adapted to engage the interior annular ridge to limit the movement of the said clutch element, the said flanges being engageable with the said clutch element and prevent turning thereof.

In testimony whereof I affix my signature in presence of two witnesses.

GEORGE A. RISK.
